UNITED STATES PATENT OFFICE

2,070,408

PORTABLE GARMENT HANGER

Nicholas C. Leidgen, Detroit, Mich., assignor of
one-sixth to Hugo O. Dietzel and two-thirds
to Clarence M. Buchanan, both of Detroit,
Mich.

Application August 21, 1935, Serial No. 37,169

2 Claims. (Cl. 211—96)

This invention relates to portable garment hangers and the object of the invention is to provide a portable garment hanger which may be engaged over the upper edge of a door so that the garments may be hung on the inside of the door.

Another object of the invention is to provide a portable garment hanger formed of two parts, a supporting bracket arranged to engage over the upper edge of the door and a hanger member pivotally supported in the supporting bracket and provided with a horizontal portion on which the garments may be hung.

A further object of the invention is to provide a portable garment hanger comprising a bracket detachably secured to the door and a hanger portion pivotally mounted in the bracket, the said hanger portion being formed to engage the door below the bracket to form an additional support for the hanger member.

A further object of the invention is to provide a portable garment hanger which requires no screws for mounting so that it may be readily removed from or replaced on any door.

These objects and the several novel features of the invention are hereinafter more fully described and claimed and the preferred form of construction by which these objects are attained is shown in the accompanying drawing in which—

Fig. 1 is a perspective view of a garment hanger embodying my invention as attached to a door.

Fig. 2 is an enlarged view of the device from the rear.

Fig. 3 is a section taken on line 3—3 of Fig. 2.

The device comprises a sheet metal bracket 1 having a portion 2 arranged to engage over the upper edge of a door and also having a depending flange 3, as shown in Figs. 2 and 3, to engage over the door as shown. The bracket portion 1 is provided with a pair of struck out lugs 4 at the top and another pair of struck out lugs 5 at the bottom. The lugs 4 and 5 are both provided with apertures in axial alignment close to the front face of the bracket 1 and the garment hanger is provided with depending ends 6 and 7 engaging in the apertures of the brackets 4 and 5 and supported close to the face of the plate 1 as shown. The garment hanger is made from a rod bent to form and comprises a horizontal portion 8 and an angular portion 9. The horizontal portion 8 is provided with an extension 10 at one side and extending upwardly therefrom is a vertical portion 11 which terminates in the return bent end 7. The portion 9 terminates

in the return bent end 6. A piece of rubber tubing 12 is fitted over the portion 10 of the hanger, as shown, in order to prevent marring of the door panel 13.

In use the bracket 1 is engaged over the top of a door so that the hanger is supported in place with the rubber tubing 12 engaging the door panel 13 as shown. The horizontal portion 3 provides a support for any of the common types of garment hangers having a hook end which may be hooked over the portion 8 and the weight of the garments on the portion 8 is supported by the portions 6 and 7 engaging in the lugs 4 and 5 and by the portion 10 engaging against the panel 13 of the door. The bracket 1 which engages over the door is made of sheet metal but is not sufficiently thick as to interfere with the closing of the door.

The device is usually hung on a closet or locker door so that the hanger is on the inside of the door and the only portion which shows from the outside is the flange 3. The hanger may be turned in the lugs 4 and 5 to any desired position and the bracket 1 may be positioned in the center of the door or near either edge as desired.

This device is very handy in connection with a closet or locker in that it provides a means for hanging garments in the space in the center of the closet and behind the door, which space is not normally used in the ordinary closet. The device may be instantly removed or replaced on the door and will support the weight of all of the garments that can be hung on the horizontal portion 8. It will be noted that the hanger portion 9 extends downwardly at an angle and supports the outer end of the horizontal portion 8 while the hook end 7 supports the inner end thereof and the off-set portion 10 together with the lugs 4 and 5 tends to hold the hanger portion 8 in the horizontal position. The entire bracket which fits over the top of the door or the flange 3 may be finished in any desired color or imitation wood graining but preferably a color which will blend with the finish of the door. The device may be easily put in a grip or suitcase by lifting the hanger-ends 6 and 7 out of the lugs 4 and 5 to disengage the hanger from the bracket 1.

From the foregoing description it becomes evident that the device is very simple and efficient in operation, may be instantly applied to or removed from a door, is composed of few parts and is of consequent low manufacturing cost and

provides a device which accomplishes the objects described.

Having thus fully described my invention, its utility and mode of operation, what I claim and desire to secure by Letters Patent of the United States is—

1. In a garment hanger, a sheet metal bracket shaped to engage over the upper edge of a door, a pair of lugs extending outwardly from one side 10 of the bracket and a substantially triangular hanger member pivotally supported in said lugs to turn on a vertical axis, the hanger member being substantially in the form of a right angle triangle and the vertical side of the right angle triangle being pivotally supported in the lugs of the bracket, the horizontal side of the right angle triangle extending from the door and the angular portion extending from the outer end of the horizontal portion back to the bracket to support the

outer end of the horizontal portion, the lower corner of the triangular hanger member being offset from the vertical side to engage against the face of the door beneath the bracket and a rubber covering extending over said off-set corner.

2. In a portable garment hanger, a bracket arranged for engagement over the upper edge of a door, a substantially triangular hanger member formed from a single metal rod and supported in said bracket member at one side of the door, the substantially triangular hanger member being provided with an integral horizontal portion beneath the bracket and a vertical portion, said vertical portion being formed to 15 provide an off-set arranged for engagement against the face of the door.

NICHOLAS C. LEIDGEN.
